(57) CLAIM

The ornamental design for a dispenser for cosmetics, as shown and described.

DESCRIPTION

1.1 is a perspective view of a dispenser for cosmetics;

1.2 is a front view thereof;

1.3 is a back view thereof;

1.4 is a left view thereof;

1.5 is a right view thereof;

1.6 is a top view thereof; and

1.7 is a bottom thereof.

The first broken lines, shown as “- - -”, in the drawings depict portions of the dispenser for cosmetics that form no part of the claimed design.

The second broken lines, shown as “- . -”, in the drawings depict the environment in which the claimed design is used that forms no part of the claimed design.
